GARMENT HANGER

Ethel A. Field, New York, N. Y.

Application October 7, 1933, Serial No. 692,558

14 Claims. (CL 223—63)

This invention relates to garment hangers and more particularly to a hanger which may be manipulated and adjusted to accommodate various types and sizes of clothing.

5 The garment hanger forming the subject matter of this invention comprises a pair of arch shaped arms which may be extended or contracted, as desired, to accommodate garments, coats and clothing of any size desired to be suspended thereon. A bracket attached to the hook from which the hanger is suspended is provided with a pair of laterally extending lugs projecting through longitudinally extending slots in the slideable arms. A spring element, attached to the 10 bracket, presses the overlapping portions of the arms into frictional contact and holds the same in adjustably assembled position. The arms may be slid together or pulled apart so as to accommodate any desired size of garment, the spring element operating to retain the arms in the position 15 in which they are adjusted. Clip members, which may be easily attached to and detached from the clothing suspended therefrom, are also laterally adjustable to accommodate the shape and size of 20 the article suspended. Notches provided in the slideable arms, are adapted to receive the straps on women's apparel and retain the garment in proper suspended position.

The hanger may be used for suspending either 25 men's, women's or children's clothing and is adjustable so as to accommodate both small and large articles suspended thereon. Coats of various sizes may be suspended directly from the arms thereof, while skirts and similar articles may be 30 suspended from the adjustable clips attached to the arms. The hanger is so made as to securely support the clothing in a neat and attractive manner, always holding the clothing in proper shape and preventing wrinkling thereof. The hanger 35 is strong and durable, economical to manufacture, and can be sold at low cost.

An object of this invention is to provide a hanger which may be variously adjusted and manipulated to accommodate a variety of garments of different shapes and sizes.

Another object of this invention is to provide a garment hanger from which a plurality of different articles may be suspended, means being provided for holding the garments in proper fixed 45 position on the hanger.

Another object of this invention is to provide a garment hanger which may be easily and quickly 50 adjusted to accommodate garments of various shapes and sizes, which may be easily and quickly attached to and detached from the garment, and

which will not tear the garment or otherwise injure the most delicate article suspended therefrom.

Still another object of this invention is to provide an adjustable hanger which is strong and durable in construction, occupies a minimum of space, is light in weight, attractive in appearance, economical to manufacture, and can be profitably made and sold within the range of ordinary low priced hangers.

In order that a clearer understanding of my invention may be had, attention is hereby directed to the accompanying drawing, forming a part of this application and illustrating certain possible embodiments of my invention.

Referring to the drawing,

Fig. 1 is a side view of the complete garment hanger, certain parts being shown in dotted lines to indicate the range of adjustment which may be made to accommodate garments of different size;

Fig. 2 is a top plan view of the hanger shown in Fig. 1, this view being taken on line 2—2 of Fig. 1;

Fig. 3 is an enlarged vertical cross-sectional view through the garment retaining clip and associated portion of the hanger, this view being taken on line 3—3 of Fig. 1;

Fig. 4 is an enlarged perspective view of the resilient leg members which form part of the clip;

Fig. 5 is an enlarged fragmentary elevational view of the hanger showing more particularly the means used for adjustably connecting the hanger arms; and

Fig. 6 is a horizontal cross-sectional view through the hanger arm connecting means, this view being taken on the line 6—6 of Fig. 5.

Similar reference characters refer to similar parts throughout the several views of the drawing and the specification.

The hanger comprises arch shaped arm portions 40 1 and 2 having the adjacent ends positioned in overlapping relationship. The arm portions may be formed of flat bars of metal, compressed paper, or composition material. The bracket member 4 45 is provided with a pair of laterally extending lugs 5 which extend through the elongated slots 3 provided in the adjacent overlapping ends of the arm portions. Lugs 5 provide a track upon which the laterally extensible arms 1 and 2 slide. A spring member 6 comprising a strip of resilient metal is 50 provided with an opening 7 at each end thereof, through which the projecting end of the adjacent lug 5 extends. As shown more particularly in Fig. 6, the spring member 6 is slightly arched so that the end portions of the spring member contact 55

- and press against the arm portion 1. An eyelet 8 extends through the aligned slots 3 in the arm portions 1 and 2 and connects the spring member 6 to the bracket member 4. The spring member 6 operates to press and hold the arm portions 1 and 2 in close frictional contact. In order to slidably adjust the arm portions laterally sufficient force must be exerted on the arm portions to overcome the friction between the parts set up by the action of the spring member 6. The arm portion 1 is provided with spaced notches *a* which are numbered to indicate the various coat sizes to which the hanger arms may be adjusted. A notch *b* is provided in the arm portion 2 opposite which the notches *a* may be selectively positioned to obtain the indicated hanger size.
- A hook member 9 from which the hanger may be suspended is swivelly connected to a lip portion 10 laterally extending from the bracket 4.
- 20 A notch 30 is cut into the upper edge of each of the arm portions 1 and 2 and is adapted to receive the strap of ladies' garments and retain the same in proper position upon the hanger. The notch may be provided with contracted mouth portions 25 forming lips 31 at each side thereof to prevent accidental removal of the garment straps from their position within the notch.
- Means are provided for suspending a variety of different garments of various sizes from the arm portions of the hanger. As shown more particularly in Figs. 1, 3, and 4, a clip member is provided at the free ends of each arm portion. The clip member comprises leg portions 12 and 13. The lower part 14 of each leg portion is flared 35 outwardly and is provided with spaced end portions 15. The upper end of each leg portion is provided with a rib 17 adapted to slide along the arm portions. A connecting pin 19 extends through an elongated slot 11 provided in the arm portions and through aligned apertures 18 provided in the raised portion 16 of the leg portions. The pin member 19 is provided with head portions 20 which retain the leg portions 12 and 13 in assembled position on the arm portions. The garment clip as thus assembled, may be slid along the elongated slot 11 and is thus adjustable to accommodate garments of different size. A pad 25 of rubber or other soft material is attached to the inside face of the spaced parts 15 of each leg portion by means of rivets 26. The garment is inserted between the spaced ends 15 of the leg portions and the garment removably held by the clamping action exerted by the leg portions 12 and 13. The leg portions 12 and 13 comprise resilient strips of metal and are retained in clamping position by means of a pin 21 extending through the elongated slots 24 provided in the leg portions. The pin 21 is provided with enlarged heads 22 operably connecting the leg portions 12 and 13. When the pin 21 and associated heads 22 are moved downwardly within the slots 24, the spaced ends 15 are drawn together so as to clamp the garment.
- 65 The garment clip is maintained in substantially vertical suspended position by means of lug 27 extending from the adjacent sides of the leg portions 12 and 13. The lug 27 projecting from one leg portion is adapted to extend into a corresponding notch 28 cut in the opposite leg portion.
- 70 When the leg portions 12 and 13 are connected together by means of the pin 19 and mounted upon the arm portions, the lugs 27 are then so arranged as to abut against the lower edge of the arm portions. The garment clip is thus given a limited 75 swinging movement.

The arm portions 1 and 2 of the garment hanger above described, are adapted to carry a coat or other garment. The arm portions may be adjusted to accommodate any size garment. Ladies' wearing apparel may also be suspended from the arm portions and the straps, which generally form part of such apparel, retained in position on the hanger by means of the notches 30. Skirts, trousers, and garments of a similar character, may be suspended from the garment clips which are laterally adjustable to accommodate garments of different size.

The garment hanger above described can thus be used to support a number of different articles of wearing apparel at the same time. The hanger is susceptible of adjustment so as to accommodate wearing apparel of different sizes and different shapes.

While certain novel features of the invention have been disclosed and are pointed out in the annexed claims, it will be understood that various omissions, substitutions and changes may be made by those skilled in the art without departing from the spirit of the invention.

What is claimed is:

1. A garment hanger comprising laterally extensible arm portions, suspension means connected thereto, means for frictionally retaining said arm portions in any selected extensible position, and garment retaining notches provided in said arm portions.

2. A garment hanger comprising arm portions, a bracket slidably connecting said arms, a spring element for frictionally retaining said arm portions in any desired adjusted position, and garment retaining notches provided in said arm portions.

3. An adjustable garment hanger adapted to support garments of different sizes comprising, slidably adjustable arm portions, size indicating means associated with said arm portions, a bracket connecting said arm portions, suspending means connected to said bracket, resilient means for frictionally retaining said arm portions in any desired adjusted position, and garment retaining notches in said arm portions.

4. An adjustable garment hanger adapted to be adjusted to accommodate garments of various sizes comprising, arc-shaped arm portions, size indicating means associated with said arm portions, a bracket slidably connecting said arm portions, a suspension hook connected to said bracket, spaced lugs projecting from said bracket into longitudinal slots in said arm portions, and resilient means connected to said bracket operative to press the overlapping portions of said arms in contact to frictionally retain said arm portions in any desired adjusted position.

5. An adjustable garment hanger adapted to be manipulated to accommodate garments of different sizes comprising, arc-shaped arm portions arranged in overlapping position, a bracket having lugs extending through elongated slots in said arm portions slidably retaining said arms in assembled relationship, and means for frictionally retaining said arm portions in any desired adjustable position.

6. An adjustable garment hanger adapted to support garments of various sizes comprising, overlapping arm portions, a bracket member, a suspension hook connected to said bracket, spaced lugs projecting from said bracket into longitudinal slots provided in said arm portions aligning and slidably connecting said arm portions in assembled relationship, means securing said

bracket to said slidable arms, and means for resiliently retaining said arm portions in any desired adjustable position.

7. An adjustable garment hanger comprising 5 arc-shaped arm portions arranged in overlapping relationship, a bracket, suspension means connected to said bracket, and a spring element connected to said bracket operative to press the overlapping portions of said arms in frictional contact so as to frictionally retain said arm portions in any desired adjusted position.

8. A combination garment hanger adapted to support several garments comprising, arm portions adapted to support a garment hung thereon, garment retaining notches in each of said arm portions, and garment suspending clips connected to each of said arm portions, said arms being laterally extensible to adjust the distance between said notches and said clips to accommodate garments of various sizes.

9. A combination garment hanger comprising, laterally extensible arm portions adapted to support a garment hung thereon, garment retaining notches in each of said arm portions adapted to retain said garment in suspended position, and clips slidably connected to each of said arm members, said clip members comprising a pair of leg portions adapted to grip a second garment therebetween.

10. An adjustable garment hanger comprising laterally extensible arm portions, size indicating means associated with said arm portions, said arm portions comprising overlapping bars of rectangular cross section, and garment clips slidably connected to each of said arm portions, said clip members comprising a pair of legs adapted

to grip the garment therebetween, and means for removably retaining said leg portions in garment gripping position.

11. An adjustable garment hanger comprising, laterally extensible arc-shaped arm portions, a pair of clip members, a longitudinal slot provided in each of said arm portions, means extending from the clip members into the slot permitting lateral adjustment thereof, said clip members each comprising a pair of resilient leg portions, 10 garment gripping pads fixed to the ends of said leg portions, and means for removably retaining said leg portions in garment gripping position.

12. A combination garment hanger comprising laterally extensible arc-shaped arm portions to 15 support a garment hung thereon, each of said arm portions having an elongated slot at one end thereof, garment supporting clip members slidably suspended from said slots said clip members comprising a pair of resilient leg portions 20 adapted to grip a second garment suspended therefrom, and means for locking said leg portions in garment gripping position.

13. An adjustable garment hanger adapted to support garments of different sizes comprising, 25 laterally extensible arm portions, suspension means connected to said arm portions, and garment retaining notches in said arm portions.

14. An adjustable garment hanger adapted to support garments of different sizes including, laterally extensible arm portions, size indicating means associated with said arm portions, and garment retaining notches provided in said arm portions.
